FOLDABLE PORTABLE CHIROPRACTOR'S TABLE

Andrew F. Branto, Los Angeles, Calif.

Application March 6, 1951, Serial No. 214,035

13 Claims. (Cl. 311—7)

1

This invention relates to a portable foldable chiropractor's table suitable for a chiropractor to use both in his office and when making house calls.

More specifically speaking, this invention relates to a chiropractor's table of the above stated kind which can be folded up into a sufficiently light, compact structure to be manually carried about like a suit case, and which can be unfolded at the place of use and there erected as a structure which will, in a satisfactory safe manner, support the body of the patient while the chiropractor is making the desired vertebral adjustments.

Although it is not broadly new to construct a chiropractor's table of the above stated kind, yet there remains ample room for improving such tables, for among other defects, as hitherto made they have not been so constructed and equipped as to be usable in nearly so advantageous and satisfactory a manner as tables of the more expensive, non-portable type.

Common defects in chiropractor's portable tables have been positioning the head rest at too high a level in relation to the adjacent part of the table, so that the patient lying on the table has been subjected to strain throughout the cervical and occipital regions; and failure to provide the table with a suitable clearance to accommodate the thyroid cartilage of a patient in a prone position.

Also there remains in such tables, considerable room for improving the means for supporting the thoracic and abdominal portions of the body of a patient when lying in a prone position upon the table, in such a manner that a more specific, effective vertebral adjustment may be performed.

Accordingly, among the objects of the present invention are: to provide an improved arrangement of spring supported table top members which will underlie the thorax and abdomen of a patient when he is in a prone position upon the table; to provide for a patient in said position ample clearance in the proper place to avoid pressure upon the thyroid cartilage; and to improve in various other particulars upon the required spring structures and means for maintaining the various parts of the unfolded, erected table in the proper operative relations to each other.

Other objects, advantages, and features of invention will hereinafter appear.

Referring to the accompanying drawings, which illustrate a preferred, reduced to practice embodiment of the invention,

2

Fig. 1 is a top plan view of the entire table shown in its unfolded, erected position, ready for use.

Fig. 2 is a side elevation of the table structure shown in Fig. 1, a patient being shown lying thereupon in the prone position. In order to disclose structure that would otherwise be concealed and to contract the view, parts of certain legs are broken away. A broken line indicates a depressed position of the abdominal support.

Fig. 2a is an enlarged, fragmentary sectional detail taken approximately on the plane indicated by line 2a—2a on Fig. 2.

Fig. 3 is a horizontal section looking up from angular line 3—3 of Fig. 2. Parts are broken away to economize space.

Fig. 4 is a vertical section on angular line 4—4 of Fig. 3, parts being broken away to contract the view, and broken lines indicating depressed positions of some parts. The front, headward part of a patient lying prone on the table is shown in this view.

Fig. 4a is a perspective view of the wedge shaped member shown in the adjacent portion 25 of Fig. 4.

Fig. 5 is a cross section on line 5—5 of Fig. 4, the legs being fragmentarily shown.

Figs. 6 and 7 are enlarged fragmentary, sectional details of leg bracing structures, the leg associated therewith being shown in the former view in the fully extended position, and in the latter view partly in swing. In Fig. 7 the screw bolt which passes through the slotted link, and its nut are shown in a detached, adjacent relation to the parts with which they co-operate.

Fig. 8 is a perspective view looking at the open side of the main casing section and illustrating how the remaining portion of the table is fitted thereto in the operation of placing the table in its folded up condition shown in Fig. 10. Leg structures and some other parts are omitted to simplify the view.

Fig. 9 is an enlarged, fragmentary section taken on the plane indicated by line 9—9 of Fig. 8.

Fig. 10 is a perspective view of the folded up table looking at that side of the headrest, thoracic, and abdominal supports which is up- 40 permost when the table is adjusted for use.

Fig. 11 is an enlarged, fragmentary section on the plane indicated by line 11—11 on Fig. 10.

Referring in detail to the drawings, and at first more particularly to Figs. 1 and 2, main parts of the table shown are the long table 55 top section 15, which supports the leg and hip

portions of the patient's body 16, said section 15 being shaped as an elongated, rectangular box with an open side facing downwardly; the abdominal support 17, detachably connected at its rear end to the front end of said section 15 by a hinge structure 18; the thorax support 19, deeply notched at 19a to accommodate the thyroid cartilage and linked to said abdominal support by a pair of underlying, resilient plates 20 (see Figs. 3 and 4); the pair of laterally adjustable twin head rest members 21, the upper surfaces of which are at a somewhat lower level than the upper surface of the thorax support 19, to which support they are hinged; and various leg structures and linkage which will be described later.

The front end portion of erected table structure is supported by a pair of front legs 25, at its side of the table each of said legs being foldably fastened to a front corner portion of the thorax support 19 by means of a clip 26 of an inverted U shape, small, nut carrying bolts 27 fastening the legs to the clips. Not far from their lower ends said legs 25 are rigidly linked together by a round crossbar 28. Said crossbar 28 carries at its midlength a pair of upwardly projecting fingers 29, a bridge pin 30 connecting the upper end portions of said fingers.

An angle iron rail 31 underlies transversely the front end portion of the pair of headrests 21, said rail having through it near each end a longitudinal slot 32 which slidably receives a threaded pin 33 fixed to and projecting downwardly from the overlying head rest 21. Said pin 33 carries a winged clamping nut 34, the pair of pins and nuts thus provided being part of the arrangement which supports the two head rest members 21 in such a manner that they may be horizontally adjusted to vary the space between them, and may be releasably secured in the selected adjusted position.

With the aforesaid angle iron rail 31 co-operates an inclined head rest bar 36. Said bar has a clip 37 swingably pinned to its upper end, said clip being apertured to receive a pin 38 which secures said bar to the midlength part of the angle iron 31. The lower end of said bar 36 is flattened and is provided along its lower edge with a series of spaced apart notches 39. In erecting the table the operator will apply the proper notch 39 to the aforesaid crossbar 28 to support the front end of the pair of headrests 21 at the desired height.

To the rear part of the lower face of each headrest member 21 is secured a front hinge wing 45 with which co-operates a rear hinge wing 46 attached to the front part of the lower face of the adjacent side portion of the aforesaid thorax support 19. The hinge curls of each of these hinge wings are considerably spaced apart, as shown, so that a considerable shifting of each hinge plate or wing 45 is possible along the hinge pin 47. This shiftable feature renders possible the already mentioned adjusting of the headrest members 21 toward and from each other.

A means for yieldingly linking the rear end portion of the thorax support 19 to the front end portion of the abdominal support 17 has already been mentioned as comprising a pair of resilient plates 20. Each end portion of each of these plates is preferably widened, as well shown in Fig. 3, to receive a set of front screwbolts 58 and of rear screw bolts 51, by which said plates are securely anchored to the overlying structures

in flatwise engagement with them. A considerable portion of the length of each plate 20 is in a detached relation to the rear end portion of the thorax support 19, so as to make it easier to depress the front part of the abdominal support 17.

The already mentioned hinge structure 18, whereby the abdominal support 17 is connected to the rear section 15 of the table top comprises a front set of four hinge wings 55 shown secured by screw bolts 56 to the lower face of the rear end portion of said abdominal support. These hinge wings are all pivoted upon a removable hinge pin 57 which extends across substantially the entire width of said abdominal support. The hinge structure 18 is completed by providing the pair of elongated, resilient hinge wings 58 each of which, in a flatwise manner, underlies the rear table top section 15 and is attached thereto by two pairs of screw bolts 59. Said bolts 58 are located near the rear ends of said wings, so that a considerable space intervenes between them and the pivot pin 57 around which the front end portions of the wings are curled. Because of this arrangement, when a downward thrust is applied to the lumbar region of a patient on the table the rear part of the abdominal support will yield, as indicated by broken lines in Fig. 4, thus adding to the comfort and safety of the patient.

The medial pair of table top supporting legs 60 is swingably connected to interior front corner portions of the box-like rear section 15 of the table, which section includes the downwardly directed front end wall 61, twin side walls 62 and the rear end wall 63, the attaching means 64 for these legs being similar to the already described attaching means for the front legs 25. Also a crossbar 66 connects the lower portions of legs 60, said crossbar at its midlength carrying a finger and bridge pin structure 67 like the already described structure shown in Fig. 2a. With the two bridge pins thus provided co-operates a link bar 68, which is laterally notched at each end with notches which fit over the two bridge pins and thus rigidly link together the horizontal crossbars 28 and 66 and through them assist in locking the medial and front pairs of table legs in their upstanding position. However, additional locking means is provided for said two pairs of legs, this locking means, illustrated in Figs. 6 and 7, being of the same construction for each of the four legs of said two pairs. Each leg 25 (or 60) carries, downwardly spaced from its upper end, an inwardly projecting pin 70 to which is pivoted one end of a lower strap metal link 71, said link at its opposite end being pivoted at 72 to the midlength portion of an upper co-operating strap metal link 73. In the midlength portion of said lower link 71 is a longitudinal slot 74. The upper link 73 has a deep notch 75 cut longitudinally into its lower end portion. With this notch and slot 74 co-operate a bolt 76 provided with a winged clamping nut 77. When said notch 75 is aligned with the slot 74 said bolt and nut are utilized to clamp the linkage in the bracing position shown in Fig. 6. The slot 74 is sufficiently long to allow the bolt 76 to be moved out of the way of the inswing end of the link 73 so that the bolt does not have to be removed at any time. A stop lug 73a is carried by link 73.

The pairs of legs 25 and 60 are both prevented from swinging either forwardly or backwardly

when the linkage is adjusted to the extended position shown in Fig. 6.

The leg structure is completed by providing a rear pair of legs 78 which when extended are held against swinging movement by a linkage 79 like that shown in Figs. 6 and 7.

When the table is in its erected position with a patient lying thereon, it is sometimes desirable to lock the rear end portion of the abdominal support 17 against material depression from upper position thereof shown in full lines in Fig. 4. For this purpose, an adjustable locking member 80 is swingably mounted upon a pair of eyebolts 81 which project inwardly from the front end wall 61 of the rear table top section 15. Each end portion of said member 80 is provided with a short horizontal run 82 which is positioned to be crowded under the front end portion of the already mentioned hinge wing 58 at its side of the table, so as to prevent depression of the hinge wings 58 when said member 80 is in the upswung position. Said end wall 61 is provided with apertures 61a through which said elongated hinge wings 58 extend and beyond which they project somewhat.

A wedge shaped member 85 (see Fig. 4a), is used to give the desired contour and stability to the thorax support 19, being embedded, with its thick end directed forwardly, in a cushioning material 86 contained in a covering 87. Said member 85 has a deep vertical notch 88 in the middle of its front end which conforms to the already mentioned notch 19a in the thorax support 19. The front part of the aforesaid covering 87 extends into said notch and closely overlies the front end portions of the wedge at each side thereof.

The twin headrest members 21 each contain an internal wooden frame 89, the abdominal section 17 of the table is shown with an internal, composite wooden structure 90, and the rear section 15 with an internal wooden member 91, these, preferably wooden, parts affording basal mounting means for the various attachments which have been described. In the rear sections 15 and 17 the padding is designated 92 and the coverings 93.

Preparatory to folding up the table, after removing already mentioned hinge pin 57 the rear section 15 of the table top is detached from the remaining sections thereof. The length of said rear section is slightly greater than the combined lengths of said remaining sections, making it possible, along with the adequate width of said section 15, to house the sections 17, 19 and 21 therein, in the manner illustrated in Fig. 10, it being understood that the six legs of the table have first been inswung to their folded up positions. An L-shaped locking member 95 has its shorter or basal limb 96 secured to the lower face of one side portion of the rear part of the table section 17, as shown in Figs. 3 and 11. The longer limb of said member 95 has through it an aperture which is registerable with a bore 97 through that side wall 62 to which is attached a handle 98 to be used in carrying the folded up table. Said bore 97 is located close to the open side of the box-like rear section 62, thus being positioned to receive a manually turnable locking screw 99 which co-operates with a threaded bore through a face plate 100 attached to the wall 62 as shown in Fig. 11.

In completing the folding up of the table, in order to bring the eyebolts 110 (see Fig. 8) into register with holding pins 111 carried by the end

walls of the rear table section 15, the three front table top sections are buckled in relation to each other, thus somewhat shortening their combined lengths so the operator can bring said pins and the eyes of the bolts into register. Then he will straighten out the buckled sections and complete the folding up operation. Conversely, said three table top sections are buckled outwardly preparatory to their removal.

10 It is desirable that the box-like structure of the rearmost section 15 taper a little toward its front end, making the table top structure widest at its rear end.

In the foregoing description, sufficient has been said about the operation to enable the chiropractor advantageously to erect, fold up and use the illustrated embodiment of the invention.

I claim:

1. In a table structure of the kind described, a rear table top section positioned to support the legs and hips of a patient lying thereon, a pair of elongated, normally horizontal resilient members forming hinge wings and having rear end portions underlying said rear table top section

25 and secured thereto and front end portions projecting forwardly of said rear table top section, an abdominal supporting section in advance of said rear section, said abdominal supporting section having its rear end portion hinged to said front end portions of said resilient members to swing in a vertical plane, and additional table top structure located forwardly of said abdominal supporting section to support the portions of a patient's body headward of his abdomen.

30 2. The structure set forth in claim 1, and a locking member carried by said rear table top section and adjustable to and from an underlying relation to the front end portions of said resilient members releasably to lock them against depression.

35 3. The subject matter of claim 2, and said locking member consisting of a generally U-shaped rod having its midlength portion swingably connected with said rear table top section in a 40 downwardly spaced relation to said resilient members and end portions upswingable to an underlying locking relation to the front end portions of said resilient members.

4. In a table of the kind described, a thorax 45 supporting table top section having a front edge with a spacious notch therein to afford a clearance for the thyroid cartilage of a patient lying in a prone position upon said table, and a headrest table top member in an adjacent forward relation to said thorax supporting section.

5. The subject matter of claim 4, and said thorax supporting section comprising a wedge shaped member and a cushioning material in which said member is embedded, said member having across its thicker end a vertical notch which contributes to the formation of the aforesaid clearance for the thyroid cartilage of the patient, and an outside covering for said cushioning material, a portion of said covering closely 55 overlying said notch in said member.

6. In a foldable table of the kind described, a box-like rear table top section having an open side, a plurality of additional connected table top sections, foldable legs carried by said rear table 60 top section and adjustable to support it in a connected, rearward relation to said additional sections to form a complete erected table, foldable legs carried by said additional sections, and a hinge structure which, when the table is erected 65 connects said rear section with the section next

in front, said hinge structure comprising a removable hinge pin which, when removed detaches said rear section from the section next in front thereof, said additional sections, when their legs are folded, being collectively nestable within the open side portion of said rear table top section.

7. The structure set forth in claim 6, and a locking member secured to one of said additional sections and positioned adjacent to a side wall portion of said box-like rear table top section in the aforesaid nested relation, said locking member having through it an aperture, and a manually operable locking screw carried by said side wall of said rear table top section and adjustable to and from a locking relation to said aperture.

8. The structure set forth in claim 6, and internally projecting pin carried by opposite end walls of said box-like section, and eyebolts to telescope over said pins carried by each end portion of said table top sections collectively considered, said additional sections being flexibly joined to each other, it being necessary to buckle them at their joints to position said eyebolts for telescoping over said internally projecting pins.

9. In a table structure of the kind described, a leg supported rear table top section, an abdominal supporting table top section immediately in front of said rear section, a hinge structure connecting said two sections and including a horizontal hinge pin and a pair of elongated resilient hinge wings attached by their outer end portions to the under side of said rear section in a considerably spaced relation to its front end so that the inner end portions of said wings may be sprung downwardly out of contact with said rear section, a leg supported table top section immediately in advance of said abdominal supporting section, and resilient means connecting the last recited two sections to each other, so that said abdominal supporting section is bodily depressible in relation to both of said sections with which it is connected.

10. In a portable foldable table of the kind described, a plurality of table top sections alined lengthwise of the table and in a connected relation to each other, a headrest having a rear end hinged to the foremost of said plurality of sections so that said headrest is swingable in a vertical plane, a pair of front legs in a supporting relation to the foremost of said plurality of said table top sections, said legs being spaced apart transversely of the table, a first crossbar structure linking the lower portions of the legs of said pair to each other, a second table leg and crossbar structure located rearwardly of the aforesaid pair of legs and its crossbar, a link bar connecting the midlength portions of the two

crossbars with each other, and an inclined headrest bar having an upper end portion swingably connected with the front end portion of said headrest, said headrest bar having in it a series of downwardly opening notches in a co-operative relation to said first crossbar structure and usable to support said headrest at various inclinations.

11. In a portable table of the kind described, a plurality of table top sections alined lengthwise of the table and in a connected relation to each other, a headrest having a rear end hinged to the foremost of said plurality of sections so that said headrest is swingable in a vertical plane, a pair of front legs in a supporting relation to the foremost of said plurality of table top sections, said legs being spaced apart transversely of the table, a crossbar structure connecting the legs of said pair to each other, and an inclined headrest bar having an upper end portion swingably connected with the front end portion of said headrest, said headrest bar having in it a series of downwardly opening notches in a co-operative relation to said crossbar structure and usable to support said headrest at various inclinations.

12. The subject matter of claim 11, and said crossbar structure comprising a horizontal bar and a pair of fingers upstanding therefrom longitudinally spaced apart therealong, and a bridge pin connecting said fingers, the notches of said headrest bar being in a co-operative relation to said bridge pin.

13. In a chiropractor's table, a two-part headrest member, and a hinge connecting each part of said headrest member with an adjacent rearward part of the table, said hinge including a horizontal hinge pin and a pair of hinge wings pivoted to said pin and shiftable therealong in relation to each other, so as to vary horizontally the spacing of the two parts of said headrest member from each other.
